(57) **CLAIM**

An ornamental design for a display screen with a graphical user interface, as shown and described.

DESCRIPTION

The file of this patent contains at least one drawing/photograph executed in color. Copies of the files of this patent with color drawing(s)/photograph(s) will be provided by the Office upon request and payment of the necessary fee.

FIG. 1 is a front view of an embodiment of a display screen with a graphical user interface; and,

FIG. 2 is a front view of another embodiment of a display screen with a graphical user interface.

The broken line showing of portions of the graphical user interface is included for the purpose of illustrating portions of the article and forms no part of the claimed design.

**1 Claim, 2 Drawing Sheets
